MACHINE FOR REINFORCING INSOLES

Stanley M. Griswold, Newton, and Russell K. Nash, Brookline, Mass., assignors to United Shoe Machinery Corporation, Borough of Flemington, N. J., a corporation of New Jersey

Application September 15, 1939, Serial No. 295,116

73 Claims. (Cl. 12—20)

This invention relates to machines for applying reinforcing material to insoles such as are used in the making of welted shoes, and particularly to machines for applying a strip of fabric such as duck or canvas to the inner face of the rib and to the insole adjacent to the rib.

In the manufacture of welted shoes it is customary to employ a leather insole provided with an inside and an outside channel, the lips of the channels being turned up and secured to each other to form a rib, the insole thus formed being usually reinforced by a layer of fabric such as Gem duck applied to the entire surface of the insole inside the rib and to the inner face of the rib, the fabric being trimmed flush with the top of the rib.

Tests have shown that, if the fabric is properly secured to the inner face of the rib and the adjacent portion of the body of the insole, reinforcement of the interior portion of the insole is unnecessary since, if such reinforcement is omitted, no appreciable lateral stretching of the portion of the insole between the ribs, due to lasting or other strains during the manufacture of the shoe, is found to occur and, during the wear of the shoe, the lateral stretching is found to be negligible whether or not the insole has an all-over reinforcement. The chief function of the reinforcement is, therefore, to reinforce the inseam and the inside channel, for which a strip applied to the inner face of the rib and to the body of the insole is adequate provided the strip extends inwardly of the insole far enough to avoid danger of its inner edge being caught by the needle of the inseam sewing machine.

Objects of this invention are to provide means for reinforcing insoles whereby adequate reinforcement for the rib is effected with great economy of reinforcing material, a double reinforcement of the insole at the toe is provided, the reinforcing operation may be performed very quickly and uniformly, and whereby trimming of reinforcing material extending beyond the top of the lip is obviated.

The illustrated machine comprises mechanism for supporting and feeding an insole past an operating point where an applying roll presses one marginal portion of a reinforcing strip against the body of the insole adjacent to the rib while the other marginal portion of the strip is first bent toward the direction from which the work is being fed and is then turned into a position extending lengthwise of the inner face of the rib and parallel thereto, means being provided for pressing this marginal portion against the inner face of the rib.

It is to be understood that the strip and the portion of the insole to which it is to be applied have both been previously coated with pressure-responsive cement so that instant adhesion of

the strip to the insole is effected as soon as the two are pressed together.

In order to provide a double reinforcement for the rib at the toe, a portion of the strip is first applied along one edge of the insole and then another portion of the strip is applied along the other edge of the insole, the ends of the strips overlapping each other at the toe end of the insole. In order that the same machine may be used for applying both portions of the strip, one strip is laid from the toe end of the insole toward the breast line and the other strip is laid from the breast line toward the toe of the insole.

In laying a portion of the strip against the body of the insole along the curves of the rib which occur particularly at the ball portion of the insole, it is necessary that the strip shall not move laterally with respect to the applying roll and that the length of different longitudinally extending parallel portions of the strip shall correspond to the length of the portions of the insole against which they are laid. That is, suppose a portion of the strip is being laid against the insole along the base of a portion of the rib which is convex with relation to a point on the insole located inwardly thereof with respect to the rib, then the portion of the strip laid next to the rib should be shorter than the portion laid at a distance from the rib. Accordingly, the applying roll is so constructed as to control these portions of the strip so that their lengths will substantially correspond to the lengths measured on the insole against which they are laid. This is effected, as illustrated, by dividing the applying roll into separate, freely rotatable sections or disks, one disk engaging the strip near the base of the rib, another disk engaging the part of the strip remote from the rib, and an intermediate disk engaging the strip between the inner and outer portions. Each disk is provided with sharp points or spurs long enough to hold the portion of the strip engaging the disk against substantial movement relatively to that disk. The resulting control of the strip is so accurate that the width of the marginal portion laid against the body of the insole does not vary substantially and consequently the marginal portion laid against the rib of the insole is substantially constant and no trimming of portions thereof which extend above the top of the rib is necessary.

A continuous feeding movement is imparted to the insole by positively driven upper and lower feed rolls which engage the feather portion of the insole, bend it somewhat toward the inner face of the insole and support the rib in an upright position.

The applying roll moves from an inoperative position above and to the left of the feed rolls to an operative position where its axis is substantially coincident with that of the upper feed roll.

To insure that the end of the strip will properly engage the applying roll as it moves into operative position, a finger is provided which is brought against the strip during movement of the applying roll toward the operating point and insures that the strip will properly engage the spurs on the applying roll.

To assist the operator in guiding the work to the feed rolls and applying roll, two guides are provided, one for engaging the inner face of the rib and the other its outer face, both guides being arranged close to the operating point. These guides steer the rib to the feed rolls and applying roll to enable the machine to be operated with less attention on the part of the operator. The guide engaging the inner face of the rib is released automatically by engagement of a finger with the rib at the toe of the insole.

Adjacent to the operating point is a guard against which the insole is raised after the strip has been applied to one side thereof. A pair of pivoted shear blades is arranged to move from an inoperative position into an operative position just above the guard. Means under the control of the operator is provided to move the shears into operative position and to close the shears to sever the strip, the arrangement being such that the closing movement cannot occur until the movement into operative position has been completed. To prevent interference between the applying roll and the shears, means is provided to prevent operation of the shears unless the applying roll has moved out of their path.

When starting at the toe end of the insole to apply the strip, it is desirable that the free end of the strip extend considerably beyond the applying roll and, when starting at the breast line to apply the strip, a free end of less extent is desired. Accordingly, means is provided for moving the applying roll alternately to different distances from the cutting point so that long and short free ends of the strip will be provided as required for the strip-applying operation as described.

When the applying roll is operated to bring the longer free end of the strip into contact with the insole at the toe, the strip is apt to engage the guard and be turned up away from the insole. Means is therefore provided for insuring that this upturned end be smoothed down into contact with the insole so that the end of the second strip, when it is laid, will lie over the end of the first strip.

Since the strips overlap each other at the toe end, it is desirable that cement be applied between the overlapping portions of the strips to cause them to adhere. Accordingly, a cement-applying device is arranged automatically to apply a drop or two of cement to the toe end of the first strip before the toe end of the second strip is laid over it. When the laying operation is about to be finished at the toe, it is desirable to release the guide which engages the inner face of the insole to prevent its engagement with the rib of the insole. Conveniently, therefore, the cement-applying device is carried by the inside guide, and a feeler arranged to engage the rib at the toe end of the insole acts not only to release the guide and permit it to rise but also actuates the cement-applying device.

In some cases the strip is treated with a thermoplastic stiffening agent, as disclosed in application for Letters Patent of the United States Serial No. 291,939, filed August 25, 1939, in the

name of Stanley M. Griswold. In order properly to handle a strip thus stiffened in the machine of the present invention, it is desirable to heat the strip to render it limp just prior to its reaching the applying roll, and also to heat the applying roll to prevent too sudden cooling of the strip. It is also desirable to heat the strip only while it is being applied, thus preventing overheating of a portion of the strip when the machine is at rest. Accordingly, electric heating elements are provided and the arrangement is such that when the machine is at rest the strip is removed from the heating elements and, when the applying roll is lowered to the operating point, relative mutual movements of approach between the strip and the heating elements are effected to bring them into close relation and cause the strip to be heated. A separate heating element is arranged to heat the applying roll by conduction.

These and other features of the invention will appear more fully from the following detailed description when read in connection with the accompanying drawings and will be pointed out in the appended claims.

In the drawings,

Fig. 12 is a side elevation of the head of the machine taken from the left as viewed in Fig. 7;

Fig. 12^A is a detail in rear elevation of mechanism shown in Fig. 12 for connecting the treadle to the applying roll;

Fig. 13 is a side elevation of the lower part of the machine taken from the right-hand side and

showing the treadle-controlled means for applying power to the machine;

Figs. 14 and 15 are perspective views of an insole showing successive steps of applying reinforcing material thereto;

Fig. 16 is a front view similar to Fig. 7 showing the machine provided with means for heating the tape and the applying roll; and

Fig. 17 is a view similar to Fig. 16 showing the parts in position for operating upon an insole and the strip-heating elements in operative position for heating the strip.

This machine for applying a reinforcing strip to the inside of the lip and against the body portion of an insole comprises a column 10 on which is secured a base plate 12 to which are bolted uprights 14 and 16 in which various shafts are journaled. A shaft 18 extends forwardly beyond the upright 14 and carries a lower feed roll 20 which preferably has an outer peripheral portion 22 of rubber, as shown in Fig. 4. A table 24, the top surface of which is substantially tangent to the applying roll 22 at its top point, is supported on a bracket 26 secured at 28 to the upright 14. The forward portion of the feed roll 22 is cylindrical and the rear portion 30 frusto-conical, the rear portion of the table 24 being bent downwardly to correspond to the inclination of the conical portion 30 (Fig. 11). The shaft 18 extends rearwardly beyond the upright 16 where it is provided with a gear 32 and a pulley 34. The gear 32 meshes with a gear 36 fixed to a shaft 38 which, at its forward end, carries an upper feed roll 40. The relation of the feed rolls 22, 40 is best shown in Fig. 4 where it will be seen that the feed roll 40 has a forward conical portion the taper of which corresponds substantially to that of the portion 30 of the roll 22 but tapers in the opposite direction; that is, the conical portions of the two rolls are parallel at the bite of the rolls and are adapted to receive between them the feather portion of a welt insole K and to bend it down at an angle to the plane of the body of the insole, thus causing the rib which is usually inwardly inclined to assume an upright position against the end face of the feed roll 40. The roll 40 is arranged for a limited amount of movement toward and from the roll 22 and, upon depression of a treadle 50 (Fig. 13), is moved yieldingly toward the roll 22 by mechanism to be described and at the same time power is applied to the rolls by a belt 52 engaging the pulley 34 on the shaft 18, the rolls 22, 40 being thus continuously and positively driven by power to feed the work. The belt 52 (Fig. 13) runs over a pulley 54 loose on a shaft 56 and having a friction face 58 adapted to engage and be driven by a continuously rotating friction disk 60 fast on the shaft 56. The disk 60 is driven through reducing gearing 62 by a belt 64 leading to the pulley of an electric motor 66. The motor clutch and reducing gear are mounted on a shelf 68 secured to the column 10, below the base plate 12, supported at its rear end by a brace 70, and carrying a motor switch 71. The pulley 54 is forced against the disk 60, to cause the feed rolls to be driven, by an angle lever pivoted at 72, one arm 74 of the lever engaging the hub of the pulley 54 and the other arm 76 of the lever being connected by a rod 78 to a forked member 80 pivoted at 82 to the treadle 50 which is fulcrumed at 84. Depression of the treadle 50, therefore, moves the feed roll 40 into engagement with the work and presses

the friction disks 58, 60 together to cause the rolls to be driven.

A supply of strip material S of indefinite length for reinforcing insoles is wound upon a reel 90 rotatably mounted on a frame 92 (Fig. 11) secured to the uprights 14, 16. The strip material does not need to be bias cut and may therefore be prepared by stripping up webs of material such as Gem duck which have preferably been given, while in the web, one or two coats of pressure-responsive cement such as latex cement. From the reel 90 the strip S of reinforcing material is first passed over a flanged roll 94 upon which it is held by a pin or screw 95 (Fig. 1), the roll and screw constituting a guide mounted on an arm 96 secured at 98 to an arm 100 (Fig. 1) which is secured at 102 to an arm 104 extending at right angles to a shaft 106 journaled in the uprights 14, 16. After being passed through the guide 94, the strip S passes through a guide 107 (Figs. 3 and 7) and then over a plate 108 against which it is pressed by a leaf spring 110 pivoted at 112 to an arm 113 and having an adjusting screw 114 bearing upon the spring 110 between its ends and providing means for varying the pressure of the spring against the strip S and hence the tension of the portion of the strip which is being conducted to the point of application to the insole. The plate 108 is pivoted at 116 to ears 118 secured at 120 to a bracket 122 carried by the arm 100 and is urged toward the roll 130 (Fig. 3) by a spring 123. The plate 108 (Fig. 7) carries a guide comprising a second plate 124 spaced from the plate 108 an amount slightly more than the thickness of the strip and adapted to accommodate its width. The rear part of the guide is bent toward the right (Fig. 8), that is, toward the direction from which the insole is fed, about an axis extending lengthwise of the strip so the rear marginal portion of the strip is held at an angle to the remainder of the strip (Fig. 3). The angle between the portions of the strip may be approximately a right angle but preferably is substantially more than that. The plate 108 extends downwardly beyond the guide 124, its right-hand edge 126 (Fig. 7) being convexly curved with its lower end lying close to the surface of the insole K when the machine is in operation (Figs. 3 and 8).

After leaving the guide 124, the strip S for the greater part of its width engages an applying roll, generally designated by the numeral 130, constructed as shown in Fig. 4. A stud 132 having a head 134 at one end and a reduced portion 136 at the other carries a series of three disks 138, 139 and 140, the reduced portion 136 being threaded through the lower end of the arm 100 and being further secured by a nut 142. The disks 138, 139 and 140 rotate freely on the stud 132 and are provided about their peripheries with sharp-pointed spurs 144 which are sufficiently long to pass through the fabric strip, though they need not be long enough to engage the insole because at the point of application they engage the tape after it is stuck to the insole. The spurs 144, when engaged by the strip, effectively prevent any movement of the strip with respect to the applying roll except away from the roll in the direction of the spurs. The meeting faces of the disks 138, 139 and 140 may be provided, as shown in Fig. 6, with grooves 143 extending tangentially of the stud 132, the purpose of the grooves being to cause any cement which may accidentally get in between the disks

to work out along the grooves. The applying roll is adapted to apply a major portion of the width of the strip to the body of the insole, including the inside channel from which the inner lip is raised, and accordingly the disk 140 of the applying roll has a portion of larger diameter than the other disks and the head 134 of the stud is made of a size to correspond with the diameter of the larger part of the disk 140. Moreover, the head 134, which, of course, does not rotate with the disks, is made thicker on its lower side so that the portion of its face presented to the rib is inclined away from the rib. Thus, the lower portion of the head 134 constitutes a lip 146 for tucking the marginal portion of the strip into the angle between the rib and the body of the insole, and, of course, rubs a portion of the strip adjacent to the rib against the body of the insole. The head 134 also serves to space the spurred disk 140 away from the rib and prevents the spurs from catching on the upturned portion of the strip or on the rib itself, which might result in displacing those parts. It will be seen also that the end of the upper feed roll 40 cooperates with the lip 146 to press the rib and the marginal portion of the strip together, the end face of the feed roll 40 and the head of a screw 147 which holds it on its shaft being slightly conical so that the portion which contacts with the outer face of the rib is parallel to the surface of the lip 146 which presses the strip against the inner face of the rib. Of course, if the rib is thicker at the bottom than at the top, the conicity of the feed roll 40 may be increased.

The action of the spurred disks 138, 139 and 140 which constitute the applying roll 130 is to meter the strip before it is pressed upon the insole. When the insole is traveling in a straight line perpendicular to the axis of the applying roll, the disks, of course, all travel the same distance in the same time and the length of the widthwise portion of the strip laid by each disk is the same as the distance traversed at that time on the insole by the disk which engages that portion. The three spurred disks 138, 139 and 140 engage three longitudinally extending parallel portions of the part of the strip which is laid against the body of the insole. Each of these parallel portions may be regarded as under the control of the spurs on one of the disks. Since the spurs at the under side of the disks engage the strip where it is pressed against the cement on the insole and where it is thus rendered immovable with respect to the insole, each section of the roll, that is, each disk, is by its spurs "geared" to the strip and hence to the insole. Thus, when the strip is being laid along the base of a curved portion of the rib, it will still be true that the length of each of the three parallel portions of the part of the strip laid against the body of the insole will be equal to the distance traveled by the disk which engages that portion. For example, where the rib is convex with respect to a point inwardly of the rib the disk 140 will travel a shorter distance than the disk 138, and the disk 139 will travel an intermediate distance, the difference in the distances traveled by the disks depending of course upon the radius of the curve. The strip cannot slip lengthwise or sidewise when engaged by the spurs since the spurs prevent slippage of the disk with respect to the insole. The spurs on each disk will compel the length of the portion of the strip laid by each disk to correspond

to the distance traveled along the insole by the disk. While this may cause some stretching or compression of the woven strip, with consequent distortion, the distortion is soon rectified by the reversal of the curve and as a result the strip is laid uniformly with enough of its margin turned up so that its edge will reach the top of the rib, no trimming of that edge being necessary.

In order to present a marginal portion S' (Fig. 10 5) of the strip S in a position parallel to the inner face of the rib, the portion S' of the strip which is bent forward relatively to the wider portion S² by the guide 124 is carried over the edge 126 (Fig. 3), assuming the shape indicated at 15 126' (Fig. 5) and then extends as at S³ parallel to the inner face of the rib against which it is rubbed by the lip 146 (Fig. 4). The remainder of the width of the strip S⁴ (Fig. 5) is, of course, forced by rolling pressure against the body portion of the insole and caused to adhere thereto, as illustrated in Fig. 4. The inoperative position of the strip guide and applying roll is shown in Figs. 2 and 7.

To move the parts from that position to the operative position shown in Figs. 1, 3 and 8 the following mechanism is provided: The shaft 106, on the arm 104 of which the applying roll 130 is carried, has secured thereto near its rear end a lever the left-hand arm 148 of which (Fig. 8) is connected to a rod 149 which is drawn down yieldingly by depression of the treadle 50.

To wrap the strip S around the applying roll 130 so that it will be presented properly to the insole and to cause the spurs to enter the strip, 35 30 a finger 150 (best shown in Figs. 1, 2, 7 and 8) is provided. This finger is pivoted at 152 to the arm 104 between its ends and at its upper end has a tension spring 154 connected thereto and to a pin 156 upon the arm 104, the spring 154 acting to urge the finger 150 toward the applying roll 130. The finger 150 is held in inoperative position, as shown in Fig. 7, by engagement of a rearwardly directed flange 158 thereon with a fixed, forwardly directed lug 160 on a bracket 45 40 45 163 (Fig. 12) secured to the upright 14 and, as the arm 104 swings downwardly to move the applying roll 130 into operative position, the finger moves down relatively to the lug 160 which, as the swinging movement occurs, allows the spring 154 to swing the curved lower end of the finger 150 against the strip S and press it against the applying roll 130 before the roll reaches its operating point. The finger 150 engages the strip S substantially at the point where the largest diameter of the disk 140 begins (Fig. 4) and a stop pin 161 (Fig. 7) on the arm 104 arrests the finger before it actually contacts with the applying roll 130 if no strip is between it and the roll.

In order that the insole may be properly guided to the applying roll so that the strip will be applied to the insole from end to end thereof with little or no attention on the part of the operator, two rib guides are provided, one, 162 (Fig. 7), for engaging the outer face of the rib and the other, 164, for engaging the inner face. These guides are normally raised, as shown in Fig. 7, to facilitate insertion of the work and, by movement of the treadle 50, 60 65 70 75 are lowered into positions respectively opposite the outer and inner faces of the rib (Fig. 8A). To effect this (Fig. 8) a lever arm 166 opposite the lever arm 148 is connected to a rod 168 having a threaded lower portion passing through an ear 170 connected at 172 (Fig. 11) to the rear

arm 174 of a lever fulcrumed at 176 and having a forward arm 178. The arm 178 is loosely pivoted to a bar 180 which, at its upper end, has adjustably connected to it a latch 181 (Fig. 11A) which hooks over an arm 182 pivoted at 184 to a bracket 186 secured at 188 to the frame of the machine. The outer end of the arm 182 carries the guide 164 which engages the inner side of the rib. The latch 181 is adjustably held to the bar 180 by a screw 183 passing through a slot in the latch 181 and threaded into the bar 180 which carries a pin 185 engaging an open slot in the latch 181 to prevent relative turning of the parts 181, 180. The bar 180 has a hole in its lower end through which a screw 187 loosely passes. Between the link and the head of the screw 187 is a spring 189 which permits the latch 181 to swing out as the beveled upper end of the latch engages the arm 182.

The guide 162 which engages the outer face of the rib is formed by the front end of a lever pivoted at 190 (Fig. 11) to the bracket 186 and having a rear arm 192 provided with an adjustable stop screw 194 which is in position to be engaged by the arm 174 at a point near its fulcrum so that, as the lever 174, 178 is rocked on its fulcrum 176 to lower the guide 164, the screw 194 is engaged by the arm 174 and moved upwardly to lower the guide 162 also into operative position.

The lever arm 178 is pivoted at 195 to a block 197 having a hole through which the shaft 38 passes and a downwardly open slot which straddles the shaft 18. Accordingly, as the lever 174, 178 is operated to move the guides 162, 164 toward the work, the upper feed roll 40 is brought down into engagement with the feather of the insole.

As the shaft 166 is rotated counterclockwise (Fig. 1) by depression of the treadle 50, the arm 166 moves the rod 168 upwardly until nuts 196 engage the ear 170 (Fig. 8) and lift the lever arm 174 to operate the guides as described. A compression spring 198 is provided on the rod 168 between the ear 170 and nuts 200 on the rod the purpose of which is to raise the guides when the treadle is released.

The machine is intended for laying a reinforcing strip S first on one side of an insole from the toe end to the breast line (Fig. 14) and then laying another strip S' from the breast line along the other side of the insole to the toe (Fig. 15), the strip in each case extending slightly beyond the rib at the toe and the end of the second strip being carried across the end of the first strip so as to provide a double reinforcement at the end of the toe. The method practised is fully disclosed in the application above mentioned.

To facilitate this work the machine is provided with means for cutting a strip after a portion thereof has been applied to either side of the insole. This cutting mechanism, as shown in Figs. 2, 9, 10 and 13, comprises a pair of shears which normally occupy an inoperative position (Fig. 9) and which are moved into operative position (Figs. 2 and 10) and operated to sever the strip by a solenoid the operation of which is controlled by a switch adjacent to the operator's knee. The shears (Figs. 9 and 10) comprise a blade 202 and a blade 204 pivoted to the blade 202 at 206. The blade 202 is formed on or fastened to a slide 208 arranged to move in a horizontal direction from the rearward position shown in Fig. 9 to the forward position shown in Fig. 10, the blade being thus carried from inoperative to operative position with re-

spect to the strip S. The slide 208 reciprocates on a block 209 which is supported on two struts 211 (Fig. 12) fixed to the frame, there being a pin 213 (Fig. 9) in the slide 208 engaging a slot 215 in the block 209 to limit movement of the slide 208 in both directions. A second slide 210 is arranged on top of the slide 208, and is provided with slots 212 extending lengthwise of the slide through which pass headed screws 214 to secure the two slides 208 and 210 together while permitting lengthwise relative movement thereof. The blade 204 has a portion 216 extending beyond its pivot 206 which carries a screw 218, the screw passing through an inclined slot 220 in the slide 210. Movement of the slide 210 to the right relatively to the slide 208 will cause the shear blades 202, 204 to close, as will be seen from Fig. 10 where they are in the act of closing. From this figure it will also be clear that the blades 202, 204 have their cutting edges so inclined to each other that as they close they begin to cut at the outer end and therefore cut the strip beginning at its front edge and working toward its rear edge. This has been found advantageous since, when shears having blades cutting in the usual direction from the pivot toward the points were tried in the machine, they tended when closed to push the strip out from between the blades, whereas with the arrangement shown the position of the strip is not disturbed and a clean cut across the strip is assured. Rearward movement of the slide 210 is limited by stop pins 221 set in the slide 208.

To operate the shears (Fig. 12) a bell-crank lever having an upright arm 222 and a horizontal arm 224 is pivoted at 226 to the machine frame. The arm 222 at its upper end is pivoted at 228 to the slide 210 and the horizontal arm 224 is pivoted at 230 to the armature 232 of a solenoid 234. Current for the solenoid is controlled by a push button switch 236 (Fig. 13) located behind a stiff but padded flap 238 pivoted at 240 to the column 10. By pushing the flap 238 toward the column with his knee, the operator can close the switch 236 to cause the solenoid 234 to be energized, the armature 232 being then drawn downwardly and the bell crank 222, 224 operated to move the slide 210 forwardly. This moves the shear blades 202, 204 forwardly into operative position and causes them to close to sever the strip.

To insure that the blades will not close before they reach operative position, the following mechanism is provided: A plate 242 (Figs. 2, 7, 9 and 10) is pivoted near one edge to two ears 244 on a fixed support 245 (Fig. 2) and a leaf spring 248 secured to the support by screws 246 bears against a square edge on the plate 242, thus yieldingly holding it in horizontal position but permitting the edge opposite the pivot to be lifted. Along the edge of the plate 242 opposite its pivot is a downwardly projecting ledge 250 which is beveled on its outside lower portion (Fig. 2). The screw 218 may also have its head beveled on the side toward the pivot of the plate 242. During the movement of the shears from inoperative to operative position, the screw head 218 remains in engagement with the ledge 250 and the blades cannot close. When the blades have reached operative position (Figs. 2 and 10) the screw 218 has passed beyond the ledge 250 so that the shears will close as described and when fully closed the screw 218 will be outside of the ledge 250 where it may remain during the retracting movement of the shears. When the slide 210 is

nearly fully retracted by means of a spring 252 connected to the arm 222 at one end and at the other to a pin 254 upon the frame, the blades will be opened, forcing the head 218 under the ledge 250 to its initial position.

Should the solenoid 234 be energized to operate the shears when the applying roll 130 and its carrier are in operative position, that is, when the treadle 50 is depressed, the shears would contact with the roll carrier and be likely to damage the machine. To prevent this occurrence the mechanism shown in Fig. 13 is provided. The block 80 pivoted to the treadle lever 50 at 82 is provided with a rod 260 having a bifurcated upper end pivoted at 262 to a lever 264 fulcrumed at 266 on the column 10. A rod 268 is secured to an ear 270 on the lever 264 and has its bifurcated upper end pivoted at 272 to a stop lever 274 fulcrumed at 276 on an ear 278 secured to the shelf 68. When the treadle is depressed the stop lever 274 is rocked on its fulcrum 276 to cause its front end to assume a position between the column 10 and the flap 238 so that the flap cannot be pushed toward the column far enough to close the switch 236 which causes the solenoid 234 to be energized. Hence the shears can be operated only when the applying roll is raised far enough so that the shears can pass beneath it.

The lever 264 (Fig. 13) is also utilized as part of the mechanism for moving the applying roll 130 to operative position. A rearward extension 280 of the lever 264 is connected to a rod 282 which, at its upper end, is pivoted to a lever 284 (Fig. 12^a) between its ends. One end of the lever is fulcrumed at 286 to a bracket 288 secured to the head of the machine and the other end is provided with a flattened portion 290 having a hole through which the rod 149 passes. Fixed on the rod 149 is a collar 292 having on its lower side a knife edge to engage the flattened portion 290 and slidably mounted on the rod 149 below the portion 290 is a collar 294 having on its upper side a knife edge to engage the portion 290. Between the sliding collar 294 and nuts 296 on the lower end of the rod 149 is a long compression spring 298. Depression of the treadle pulls downwardly on the rod 282 and operates the lever 284 to pull downwardly yieldingly on the rod 149 which, through the spring 298, operates the lever arm 148 (Fig. 8) to turn the shaft 106 in a counterclockwise direction to lower the applying roll 130 into operative position (Fig. 13). To raise the treadle 50 a tension spring 299 (Fig. 13) is connected at its lower end to a collar on the rod 282 and at its upper end to a bracket 301 secured to the machine head (Fig. 12).

The shaft 106 is mounted for limited endwise movement and is urged rearwardly by a spring 300 mounted on the shaft 106 between the upright 14 and a collar 302 fixed to the shaft 106. Rearward movement of the shaft is controlled by a roll 304 (Fig. 12) which engages a cam face 306 formed on a block 308 secured to the upright 16. The roll 304 is carried by the lever arm 148 at a short distance from its axis 106 and, as the lever arm 148 is operated to bring the applying roll 130 into operative position, the roll 304 rides along the surface 306 and, when the applying roll has reached substantially its operative position and is about to contact with the insole, the roll 304 passes on to a drop 310 on the cam face 306 which allows the shaft 106 to be forced rearwardly by the spring 300 and cause the lip 146 on the head 134 to be forced into the

angle between the body of the insole and the inner face of the rib, thus pressing the upturned portion of the strip against the rib R of the insole which, of course, is supported on its outer face by the slightly conical end face of the feed roll 40 and of its screw 147. Turning movement of the shaft 106 to move the applying roll 130 into operative position is limited by a stop 311 secured to the lever arm 148 which, when no insole is in the machine, engages a face 313 formed on the upright 16 and prevents the spurred roll 130 from engaging the rubber-covered feed roll 22 should the treadle 50 be depressed.

The machine is provided, adjacent to the shears 202, 204, with a guard 312 (Figs. 2 and 7) which extends forwardly beyond the ends of the shear blades when they are in operative position and thus protects the operator from contact with them when they are operating. To support the guard 312 an angular portion 314 thereof is secured at 316 to the upright 14. The outer end of the guard 312 is extended toward the right (Fig. 7) so that a portion 318 thereof lies in front of the ends of the shear blades. Beside its guarding function, the guard 312 serves as a stop to limit upward movement of the insole (Fig. 2) and thus present the insole in proper relation to the shear blades 40 for cutting off the strip. Also, on the under side of the guard 312 is a button 320 for a purpose to be explained. A pin 428 projecting upwardly from the shear blade 202 serves to prevent the free end of the strip 130 from swinging rearwardly as the applying roll 130 moves toward its operative position.

The strip S is preferably laid, as shown in Fig. 14, from the toe end of the shoe along one side to the breast line and, in order for the strip to extend somewhat beyond the rib at the toe end, a longer end portion is needed on the strip in starting the end portion than when the second strip S' is laid along the other side of the insole from the breast line to the toe (Fig. 15). Consequently, means is provided for insuring a greater extent of the free end of the strip beyond the applying roll when the strip-applying operation is started at the toe than when it is started at the breast line, mechanism for this purpose being best shown in Figs. 7 and 8. In Fig. 7 the inoperative position of the applying roll is shown as that which it assumes when the strip is about to be applied to an insole beginning at the toe end; that is, the portion of the strip extending beyond the guide 124 is long enough to extend beyond the toe when the operation is begun at the toe end. This condition is insured by the fact that before the shears were operated the applying roll and strip guide were allowed to move to a higher position when the treadle was released. This position is controlled by a link 322 pivoted to the lever arm 163 and having on its lower end a rearwardly directed pin 324 which engages one or the other of two notches 325, 327 in a tip cam 326 pivoted by a screw 328 to a plate 330. A spring 332 (Fig. 11) is provided between the head of the screw 328 and the tip cam 326 to frictionally hold the tip cam in either of its two positions which are determined by engagement of one or the other of its lower corners with the plate 12 forming part of the machine head. Supposing the machine is operated to apply a strip from the toe end of an insole toward the heel end, the link 322 will assume the position shown in Fig. 8 during that operation, the pin 324 being held in a central

position by engagement with a slot 333 formed in a plate 330 secured to the front face of the plate 330, the tip cam 326 remaining, of course, in the position shown in Fig. 7. When the breast line is reached and the treadle released, the link 322 will descend and the pin 324 will engage the shallower notch 327 of the tip cam 326 and tip the cam into the position shown in Fig. 1. Thus, the applying roll and strip guide will not rise as far as before so that when the strip is cut off the free end will be shorter and will be of the right length to start the application of the strip at the breast line of the insole when the strip S' is applied to the second side of the insole. When the treadle is released at the end of this operation, the pin of course will engage the deeper notch 325 of the tip cam 326 and the applying roll will rise higher to provide a longer free end on the strip for application to the toe end of the next insole.

When starting the operation at the toe end of the insole as the applying roll is brought into operative position (Fig. 7^A), the end of the strip engages the guard 312 and may not assume its proper position extending over the rib at the toe end. To smooth down this end of the strip and push it into position against the inner face of the rib at the toe so that the toe end of the strip S' may be laid over it, the mechanism shown in Figs. 7^A and 7^B is provided. Pivoted at 340 to the rear face of the arm 100 is a member 342 having a strip-engaging arm 344. The member 342 is normally held with its edge face against a stop pin 346 by a spring 348. A latch lever 350, also pivoted at 340, has one end pivoted at 352 to a latch 354, the other end of the lever 350 carrying an adjustable stop screw 356. The latch 354 has a corner 358 adapted to ride along an edge face 360 of the member 342, which face is curved from the pivot 343 as a center, the corner 358 being arranged to engage a lug 362 on the member 342. The latch 354 is held against the surface 360 of the member 342 by a spring 364 and, as the applying roll moves from the position shown in Fig. 7^A toward the position shown in Fig. 7^B, the stop screw 356 engages the guard 312, causing the corner 358 of the latch 354 to engage the lug 362 and swing the arm 344 in a direction to smooth down the end of the strip S and lay it against the rib of the insole K, as shown in Fig. 7^B. When this point is reached, a tail 366 on the latch 354 engages a stationary stop 368 secured to the arm 100, causing the corner 358 of the latch lever 354 to be lifted above the lug 362, whereupon the spring 348 acts to return the member 342 to its initial position against the stop pin 346.

In order that there may be cement on the outer face of the toe end of the first strip before the toe end of the second strip is laid over it, the mechanism shown in Figs. 1, 8 and 11 is provided. The arm 182 (Fig. 11) which carries the inside rib guide 164 has pivoted thereto between its ends at 370 a lever having a forward arm 372 and a rear arm 374. The rear arm 374 lies adjacent to the latch 181 (Fig. 11^A), which latch connects the arm 182 to its operating mechanism. The forward arm 372 of the lever carries a cement-applying nozzle 376 (Fig. 8) leading from a casing 378 which is supplied with cement through a tube 380 connected to a suitable tank 382 (Fig. 1) which may conveniently be mounted on the frame 92 above the nozzle 376 to provide a gravity feed. Passage of the cement through the nozzle 376 is controlled by a needle

valve having a stem 384 (Fig. 8) surrounded by a spring 386 which normally holds the needle valve closed. A trigger 388 is pivoted at 390 to a lug 392 projecting from the casing 378 and has an arm lying beneath a collar 393 on the stem 384 of the needle valve to lift the needle valve when the nozzle 376 and the lower end of the trigger 388 approach each other. The nozzle 376, since it is mounted on the arm 372 pivoted at 370 to the arm supporting the inner rib guide 164, can be moved to the left. The trigger 388, however, is prevented from movement by engagement with a lug 394 on the rib guide 164. Therefore, as the toe end of the insole is being approached in laying the second strip S' on the insole, the rib R of the insole K will strike the nozzle 376, moving it leftward relatively to the trigger 388 (Fig. 1) and causing the needle valve to be lifted so that cement will be deposited from the nozzle on to the already laid toe end portion of the first strip and the applying roll will then carry the toe end of the second strip across the toe end of the first strip, the cement serving to secure the ends of the two strips together. When this movement of the nozzle 376 occurs, the rear arm 374 engages the latch 181 and pushes it off the arm 182, thus releasing the arm 182 carrying the inside guide 164 and the nozzle 376 and allowing it to be raised by a tension spring 396 connected between the arm 182 and a stationary bracket 398 on the upright 14. Since the nozzle and inside guide 164 are thus raised out of the way of the insole rib, the applying roll can finish laying the strip up to the rib at the toe end of the insole. When this is done the treadle is released, permitting the applying roll to rise to its highest position, the pin 324 then engaging the deeper notch 325 of the tip cam 326. The insole will now be held against the guard 312 (Fig. 2), the flap 238 will be operated by the operator's knee to energize the solenoid 234, and the shears 202, 204 will advance and cut off the strip substantially flush with the top face of the guard 312, a long free end being thus left on the strip ready to begin operation on the toe end of the next insole. The button 320 on the under side of the guard 312 may now be utilized by the operator to tuck the crossed ends of the strips S, S' snugly into the angle between the rib and the body of the insole at the toe as he removes the finished insole from under the guard 312.

When a strip stiffened with thermoplastic stiffening material is to be employed for reinforcing insoles, the machine is equipped for heating the strip and the applying roll, as illustrated in Figs. 16 and 17. In the illustrated construction, a portion of the strip is held in extended condition in a substantially straight line between the guide roll 94 and the guide 124, the guide 107 keeping the strip from sagging. An arm 406 is secured at 408 to the frame 92 and to its left-hand end is pivoted at 410 a lever to the lower arm 412 of which are secured two heating elements 414 which are arranged in tandem but are connected in parallel to receive current through wires 416 from any suitable source. The upper arm of the lever 412 is bifurcated to form a short branch 417 and a long branch 418 to which is secured one end of a tension spring 420 the other end of which is secured to a pin on the arm 406. Between the branches 417, 418 of the lever 412 is pivoted, on the same axis 410 as the lever 412, an arm 421 carrying a stop pin 423 which is normally held by a spring 425 (Fig. 17) against the short branch 417. A heating element 422 is con-

nected to the arm 100 near its lower end. The heating unit is supplied with current through wires 424 and serves to heat by conduction the applying roll 130 and the adjacent parts.

By referring to Fig. 16 it will be seen that as the applying roll 130 is moved toward the operating point about the center of the shaft 106 the portion of the strip which extends in a straight line from the guide 124 to the guide 94 with its mid portion supported by the guide 107 will be brought into a position nearly parallel with the exposed faces of the heating elements 414. Just before the applying roll 130 reaches the operating point the screw 95 (Fig. 16) comes in contact with the arm 421 and swings the lever 412 on which the heating elements 414 are mounted about its pivot 410 into the position shown in Fig. 17 where its position with respect to the skirt is determined by its coming in contact with the guide 107. The exposed faces of the heating elements 414 are now parallel to the strip and spaced therefrom a short distance. After this occurs further movement of the applying roll into operative position is permitted since the arm 421 can yield against the spring 425 to permit such movement. Therefore with the applying roll 130 in operative position, the strip, as it moves along, is exposed to intense radiation from the heating elements 414 before it reaches the guide 124, which also is heated by the element 422, and then passes directly to the heated applying roll 130 which applies it to the insole. In this way the stiffened strip is rendered very limp so that it can be applied to the insole as readily as an unstiffened strip.

It will be noted (Fig. 17) that the cement-applying device 378 is omitted but that a feeler 426 occupies the position of the nozzle 376. The feeler is formed on a lever similar to the lever 372, 374 and when the feeler engages the rib of the insole the lever is moved to release the latch 181, thus allowing the inner rib guard 164 to be raised above the rib to permit passage of the rib under it.

Either or both of the heating devices 414, 422 may be employed whether or not the strip has been impregnated with thermoplastic material; for example, by using the heating device 414 in connection with laying strip material having a coating of latex cement but not impregnated with stiffening material, it has been found that a very superior bonding of the strip to the insole is obtained.

Having thus described our invention, what we claim as new and desire to secure by Letters Patent of the United States is:

1. In a machine for applying a reinforcing strip to a ribbed insole, means for feeding the insole, a roll for applying one marginal portion of the strip to the body of the insole, means for turning the other marginal portion of the strip at right angles to the first portion, and means for forcing said other marginal portion against the inner face of the insole rib.

2. In a machine for applying a reinforcing strip to a ribbed insole, means for feeding the insole, means for supporting the outer face of the rib to hold it in an upright position, means for laying one marginal portion of the strip against the body of the insole, means for turning another marginal portion of the strip substantially at right angles to the portion applied to the body of the insole, and means for forcing said turned marginal portion against the inner face of the supported insole rib.

3. In a machine for reinforcing ribbed insoles, the combination of means for supporting and feeding an insole past an operating point, an applying roll, means for guiding a strip of reinforcing material to the applying roll with a marginal portion thereof directed toward the direction from which the sole is fed, means adjacent to the applying roll for turning said marginal portion into a position parallel to the inner face of the rib, and means for pressing said marginal portion against the rib while the applying roll presses the remainder of the strip against the body of the insole.

4. In a machine for applying a reinforcing strip to a ribbed insole, means for feeding the insole horizontally with its ribbed face exposed, a roll for applying one marginal portion of the strip to the body of the insole, a guide for conducting the strip to the roll, said guide being constructed to bend the other marginal portion of the strip toward the direction from which this insole is fed, means acting as the strip approaches the applying roll to turn said other marginal portion of the strip at right angles to the portion being laid against the body of the insole, and means for forcing said other marginal portion against the inner face of the insole rib.

5. In a machine for reinforcing ribbed insoles, the combination of a feed roll, a second cooperating feed roll having a conical end face adapted to support the outer face of the rib, an applying roll adapted to engage one marginal portion of the strip and press it against the body of the insole, means for bending the other marginal portion of the strip toward the direction from which the work is fed, a plate having an edge adjacent to the applying roll across which said other marginal portion is drawn into a position parallel to the inner face of the rib, and means for forcing said other marginal portion against the inner face of the rib.

6. In a machine for applying a reinforcing strip to a ribbed insole, means for supporting and feeding the insole, a guide for presenting the strip in a position substantially perpendicular to the insole with a marginal portion bent out of the plane of the remaining portion, an applying roll acting to lay said remaining portion of the width of the strip against the body of the insole, a plate having an edge adjacent to the applying roll about which the bent margin of the strip is passed to present it in a position parallel to the inner face of the rib of the insole and extending lengthwise thereof, and means for rubbing said bent portion into the angle between the rib and the body of the insole and against the inner face of the rib.

7. In a machine for applying a reinforcing strip to a ribbed insole, means for supporting and feeding the insole, means for supplying a reinforcing strip of indefinite length, a guide for presenting the strip in a position substantially perpendicular to the insole with a marginal portion bent out of the plane of the remaining portion, an applying roll acting to lay said remaining portion of the width of the strip against the body of the insole, a plate having a curved edge adjacent to the applying roll about which the said marginal portion is passed to present it in a position parallel to the inner face of the insole rib, and means for forcing said marginal portion against the inner face of the rib.

8. In a machine for applying a reinforcing strip to a ribbed insole, an applying roll, means including a table for supporting and moving the

insole relatively to the applying roll, means for supplying a reinforcing strip to the applying roll in a position substantially perpendicular to the table, a plate adjacent to the applying roll having a curved edge about which a marginal portion of the strip extending beyond the applying roll is carried to present it in a position parallel to and extending lengthwise of the inner face of the insole rib, and means for pressing said portion against the rib while the applying roll is forcing another portion of the strip against the body of the insole.

9. In a machine for applying a reinforcing strip to a ribbed insole, means for supporting and feeding the insole, means for supplying a reinforcing strip of indefinite length, a guide for the strip whereby the strip is presented to the insole in a position substantially perpendicular to the insole with a marginal portion bent out of the plane of the remaining portion, an applying roll acting to lay said remaining portion of the strip against the body of the insole, a plate having an edge adjacent to the applying roll about which the bent margin of the strip is passed to present it in a position parallel to the inner face of the insole rib, and means for rubbing said bent portion into the angle between the rib and the body of the insole and against the inner face of the rib to the top thereof.

10. In a machine for applying a reinforcing strip to a ribbed insole, an applying roll, means for supporting and moving the insole relatively to the applying roll, means for supplying a reinforcing strip to the applying roll in a position substantially perpendicular to the plane of the insole, a plate adjacent to the applying roll having an edge about which a marginal portion of the strip extending beyond the end of the applying roll is carried to present it in a position parallel to the inner face of the insole rib, and means for pressing said portion against the rib while the applying roll is forcing the remainder of the strip against the body of the insole.

11. In a machine for applying strips to the marginal portions of insoles, the combination of means for feeding an insole past an operating point, means for applying a strip to the insole at the operating point, and means for controlling the strip laid by the applying means so that the lengths of longitudinally extending parallel portions of the strip taken from the supply in a given period of time will correspond to the lengths measured on the insole against which they are laid while said strip is being progressively applied at a predetermined distance from a curved edge of the insole.

12. In a machine for applying strips to the marginal portions of insoles, the combination of means for feeding an insole past an operating point, and a freely rotatable applying roll acting at the operating point to lay the strip upon the insole, said roll being divided into a plurality of disks, each disk being provided with spurs on its periphery whereby the length of each longitudinally extending parallel portion of the strip applied by each disk in a given time will correspond to the distance traveled in that time by the disk in contact with the strip upon the insole whether the strip is being laid parallel to a curved portion of the insole edge or parallel to a straight portion thereof.

13. In a machine for reinforcing ribbed insoles with strips of fabric, the combination of means for feeding an insole past an operating point, means for applying a marginal portion of the strip

5 to the inner face of the rib, and a roll for applying the remainder of the strip to the insole, said roll comprising a plurality of freely rotatable disks having spurs on their peripheries, said disks insuring that the length of each longitudinally extending parallel portion of the part of the strip laid by the roll in a given time will correspond to the distance traveled in that time by each disk as the disks follow the curvature of the rib.

10 14. In a machine for applying reinforcing strips to ribbed insoles, the combination of means for feeding an insole past an operating point, means acting at the operating point to apply a marginal portion of the strip to a face of the rib, and means at said operating point for applying the other marginal portion of the strip to the insole at the base of the rib, said means acting to control the lengths of various longitudinally extending parallel portions of the strip so that the lengths of said longitudinally extending parallel portions of the strip will correspond to the lengths measured on the insole against which they are laid.

15 15. In a machine for applying strips of material to insoles, the combination of a pair of feed rolls for gripping and feeding the marginal portion of an insole, one feed roll extending beyond the other to support the insole, means for positively driving the feed rolls continuously, strip guiding means, and a freely rotatable applying roll opposed to the longer feed roll and acting to press the strip upon the adjacent face of the insole as it is fed.

20 16. In a machine for applying a reinforcing strip to the marginal portion of a sole member, positively driven upper and lower feed rolls for continuously feeding the sole member past an operating point, one feed roll being longer than the other to support a face of the sole member, and a freely rotatable applying roll acting at an operating point over the longer feed roll to lay the strip against the marginal portion of the face of the sole member which is opposite the supported face thereof.

25 17. In a machine for applying strips to the marginal portions of insoles, the combination of means for feeding an insole past an operating point, a strip guide for presenting a strip at the operating point, and a freely rotatable applying roll having spurs in its periphery adapted to prick through the strip and prevent movement of the strip with respect to the roll.

30 18. In a machine for applying reinforcing strips to insoles, a strip-applying roll comprising a plurality of freely rotatable disks, each disk having about its periphery a series of spurs.

35 19. In a machine for applying strip material to insoles, the combination of means for feeding an insole past an operating point, and an applying roll acting to lay a strip on the insole at the operating point, said roll comprising separate disks with spurs on their peripheries and acting to lay the strip against the body of the insole.

40 20. In a machine for applying strip material to insoles, the combination of means for feeding an insole past an operating point, and a freely rotatable strip-applying roll acting at the operating point to lay the strip against the body of the insole, said roll having spurs on its acting face to prevent lateral movement of the strip with respect to the roll.

45 21. In a machine for applying strip material to insoles, the combination of means for feeding an insole past an operating point, and a strip-applying roll acting at the operating point to lay

a strip against the body of the insole, said applying roll comprising separate freely rotatable spurred disks.

22. In a machine for applying a reinforcing strip to the marginal portion of a sole member, positively driven upper and lower feed rolls for continuously feeding the sole member past an operating point, and an applying roll comprising a plurality of disks provided with peripheral spurs, said applying roll acting at the operating point to lay the strip against the marginal portion of the sole member.

23. In a machine for applying strip material to insoles, the combination of upper and lower feed rolls on parallel axes and engaging respectively the upper and lower sides of a marginal portion of an insole, the lower feed roll being longer than the upper feed roll, means for driving the rolls to feed the sole past an operating point, a strip guide for presenting the end of a strip of material at an operating point over the longer feed roll, and a freely rotatable applying roll acting at the operating point to press the strip of material against the upper face of the insole as it is fed past said point.

24. In a machine for applying strip material to ribbed insoles, the combination of a cylindrical roll having a conical end, said roll engaging the unribbed side of the insole with its conical end opposite the feather of the insole, a cooperating roll having two conical surfaces one engaging the feather of the insole and the other the outer face of the rib, and an applying roll having spurs on its acting face for laying the strip against the body of the insole, said spurs preventing lateral movement of the strip with respect to the roll.

25. In a machine for applying strip material to ribbed insoles, the combination of a cylindrical roll having a conical end, said roll engaging the unribbed side of the insole with its conical end opposite the feather of the insole, a cooperating roll having two conical surfaces one engaging the feather of the insole and the other the outer face of the rib, an applying roll comprising separate disks with spurs on their peripheries for laying the strip against the body of the insole, and means for spacing the applying roll from the rib to prevent contact of the roll therewith.

26. In a machine for reinforcing ribbed insoles, the combination of a pair of continuously driven feed rolls arranged to engage the feather portion of an insole, a strip guide for presenting a strip of reinforcing material to the body of the insole adjacent to the inner face of the rib, a freely rotatable applying roll acting to force a portion of the strip against the body of the insole, and means for laying another portion of the strip against the inner face of the rib and for spacing the applying roll from the rib.

27. In a machine for applying strip material to ribbed insoles, the combination of a cylindrical roll having a conical end, said roll engaging the unribbed side of the insole with its conical end opposite the feather of the insole, a cooperating roll having two conical surfaces one engaging the feather of the insole and the other the outer face of the rib, said rolls acting to present the rib in upright position, means for laying the strip against the inner face of the rib, and a roll freely rotatable on an axis parallel to the plane of the insole for laying the strip against the body of the insole.

28. In a machine for applying strip material to ribbed insoles, the combination of a cylindri-

cal feed roll having a conical end portion, said roll engaging the unribbed side of the insole with its conical portion opposite the feather of the insole, a cooperating feed roll having two conical surfaces one engaging the feather of the insole and the other the outer face of the rib, an applying roll freely rotatable on an axis parallel to the plane of the insole for laying one marginal portion of a strip against the body of the insole and means for simultaneously rubbing the other marginal portion of the strip against the rib.

29. In a machine for applying strip material to ribbed insoles, the combination of means for feeding an insole past an operating point, a strip applying roll acting at the operating point to apply a marginal portion of the strip to the body of the insole, said applying roll comprising a stud on which a plurality of disks are mounted for free rotation, and a lip fixed to said stud and acting to lay another marginal portion of the strip against the rib of the insole and to force a narrow portion of the strip adjacent to the rib against the body of the insole.

30. In a machine for applying strip material to ribbed insoles, the combination of a cylindrical feed roll having a conical end portion, said roll engaging the unribbed side of the insole with its conical portion opposite the feather of the insole, a cooperating feed roll having two conical surfaces one engaging the feather of the insole and the other the outer face of the rib, an applying roll comprising separate freely rotatable spurred disks for laying one marginal portion of a strip against the body of the insole, and means for simultaneously rubbing the other marginal portion of the strip against the rib.

31. In a machine for reinforcing welt insoles, the combination of continuously driven upper and lower feed rolls arranged to engage the feather portion of an insole, the upper feed roll engaging the outer face of the rib, a strip guide for presenting a strip of reinforcing material to the body of the insole adjacent to the inner face of the rib, a freely rotatable applying roll acting to force a portion of the strip against the body of the insole, and means carried by the shaft of the applying roll for laying another portion of the strip against the inner face of the rib.

32. In a machine for applying strip material to ribbed insoles, the combination of a cylindrical feed roll having a conical end portion, said roll engaging the unribbed side of an insole with its conical portion opposite the feather of the insole, a cooperating feed roll having two surfaces one engaging the feather of the insole and the other the outer face of the rib, an applying roll comprising a stud on which a plurality of disks are mounted for free rotation, said roll acting to lay the strip against the body of the insole, and a lip fixed to said stud and acting to rub the other marginal portion of the strip against the rib.

33. In a machine for applying a reinforcing strip to a ribbed insole, means for advancing the insole past an operating point, a freely rotatable spurred applying roll movable into and out of operative position with respect to said operating point, means for presenting a strip to the applying roll, and means operating as the applying roll moves into operative position to press the strip against the spurs on the applying roll.

34. In a machine for applying a reinforcing strip to an insole, means for advancing the strip past an operating point, an applying roll movable into and out of operative position with respect

to said operating point, said roll comprising a plurality of freely rotatable disks, each disk having a series of spurs on its periphery, means for guiding the strip to the roll, and means operating as the roll approaches the operating point to press the strip against the spurs on the roll, said means remaining in position during the application of the strip to the insole.

35. In a machine for applying a reinforcing strip to a ribbed insole, means for advancing the insole past an operating point, an applying roll movable into and out of operative position with respect to said operating point, a carrier for the applying roll, a strip guide on said carrier, a finger mounted on the carrier, means for urging the finger toward the applying roll, and means arranged to permit the finger to engage the strip on the applying roll during the movement of the applying roll toward the operating point.

36. In a machine for applying a reinforcing strip to a ribbed insole, means for advancing the insole past an operating point, an applying roll movable into and out of operative position with respect to said operating point, a carrier for the applying roll, a strip guide on the carrier, a finger mounted on the carrier, a spring urging the finger toward the applying roll, and means arranged to permit the finger to engage the strip and position it in operative relation to the applying roll during the movement of the applying roll toward the operating point.

37. In a machine for applying a reinforcing strip to a ribbed insole, means for advancing the insole past an operating point, an arm arranged to swing about a center to carry its end into and out of operative position with respect to said operating point, an applying roll on the end of said arm, a strip guide carried by the arm, a finger mounted on the arm and having a flange, a stationary lug engaging the flange, and a spring urging the finger toward the applying roll, the spring acting as the arm swings relatively to the lug to move the finger toward the roll.

38. In a machine for reinforcing ribbed insoles, the combination of means for applying a strip of material to the body of the insole and to the inner face of the rib, means for feeding the insole toward the applying means, and guides engaging the inner and outer faces of the rib to direct the insole to the applying and feeding means.

39. In a machine for reinforcing ribbed insoles, the combination of means for applying a strip of material to the body of the insole and to the inner face of the rib, means for feeding the insole toward the applying means, and guides initially out of the way of the rib and movable into position to engage the inner and outer faces of the rib to direct the insole to the applying and feeding means.

40. In a machine for reinforcing ribbed insoles, the combination of means for applying a strip of material to the body of the insole and to the inner face of the rib, upper and lower rolls for feeding the insole toward the applying means, a table adjacent to the lower feed roll to support the insole, and guides above the table and engaging the inner and outer faces of the rib to direct the insole to the applying and feeding means.

41. In a machine for applying a reinforcing strip to a ribbed insole, means for feeding the insole, strip-applying means, an insole-support-

ing table adjacent to the feeding means, a guide to engage the outer face of the rib, a guide to engage the inner face of the rib and cooperating with the outer guide to guide the insole over the table to the applying means, said guides being initially in raised position, and manually operated means for moving the guides into operative position to engage respectively the inner and outer sides of the rib.

42. In a machine for applying a reinforcing strip to a ribbed insole, upper and lower feed rolls adapted to receive the feather of the insole between them, a strip-applying roll movable from a remote position to a position adjacent to the feed rolls, means for supplying a strip of reinforcing material to the applying roll, a guide engaging the outer face of the rib, and a guide engaging the inner face of the rib and cooperating with the outer guide to direct the insole to the applying roll.

43. In a machine for applying a reinforcing strip to a ribbed insole, upper and lower feed rolls, a strip-applying roll, means for supplying a strip of reinforcing material to the applying roll, an insole-supporting table adjacent to the lower feed roll, a guide to engage the outer face of the rib, a guide to engage the inner face of the rib and cooperating with the outer guide to guide the insole over the table to the applying roll, said guides being initially in raised position, and manually operated means for moving the guides into operative position to engage respectively the inner and outer sides of the rib.

44. In a machine for applying a reinforcing strip to a ribbed insole, upper and lower feed rolls adapted to receive the feather of the insole between them, a strip-applying roll movable from a remote position to a position adjacent to the feed rolls, means for supplying a strip of reinforcing material to the applying roll, a guide engaging the outer face of the rib, a guide engaging the inner face of the rib and cooperating with the outer guide to guide the insole to the applying roll, said guides being initially in raised position, and treadle-operated means for moving the applying roll into position to apply the strip to the insole and for moving the guides into operative position to engage respectively the outer and inner side of the rib.

45. In a machine for applying a reinforcing strip to a ribbed insole, the combination of means for feeding the insole, means for applying the reinforcing strip to the body of the insole and to the inner face of the rib, a guide engaging the inner face of the rib, and a feeler arranged to engage the rib of the insole and release said guide for movement away from the insole rib.

46. In a machine for applying a reinforcing strip to a ribbed insole, the combination of means for feeding the insole, means for applying the strip to the body of the insole and to the inner face of the rib, a guide engaging the inner face of the rib, a spring for lifting the guide, a latch for holding the guide in operative position, and a feeler adapted to engage the insole rib and release the latch to permit the guide to rise.

47. In a machine for applying a reinforcing strip to a ribbed insole, the combination of means for feeding the insole, means for applying the strip to the body of the insole and to the inner face of the rib, a guide engaging the inner face of the rib, a spring for lifting the guide, means for holding the guide in operative position, and a feeler adapted to engage the insole rib and

release the guide from its holding means to permit the guide to rise.

48. In a strip-laying machine, means for feeding the work, means for applying a strip to the work, a guard against which the work may be raised at the conclusion of the applying operation, a pair of shears arranged for bodily movement into operative position adjacent to said guard, and means for operating the shears, after the bodily movement has ceased, to sever the strip.

49. In a strip-laying machine, means for feeding the work, a pair of shears arranged for bodily movement from an inoperative position to a position in which the blades embrace the strip, and means for operating the blades only after their bodily movement has ceased.

50. In a strip-laying machine, means for applying a strip to the work, a guard against the lower face of which the work may be presented for cutting the strip, a shear blade movable from an inoperative position to an operative position above the guard, a cooperating blade pivoted to the shear blade, and means for moving the shear blades bodily into operative position and thereafter operating the pivoted blade to sever the strip without bodily movement of the blades.

51. In a strip-laying machine, means for applying a strip to the work, a guard against which the work may be raised at the conclusion of an applying operation, a slide arranged to move toward the guard and having its end formed as a shear blade, a lever pivoted to said slide having one end formed as a shear blade cooperating with the first-mentioned shear blade and its other end carrying a stud, a second slide movable in the same direction as the first slide and having an inclined slot engaging said stud, and means for operating said second slide to move the shear blades into operative relation to the strip applied to the work and then operating the pivoted shear blade to sever the strip.

52. In a strip-laying machine, means for applying a strip to the work, a first slide arranged to move in a plane perpendicular to the direction of presentation of the strip and having its end formed as a shear blade, a lever pivoted to the first slide having one end formed as a shear blade cooperating with the first-mentioned shear blade and its other end carrying a stud, a second slide movable in the same direction as the first slide and having an inclined slot engaging the stud, a pivoted plate having a ledge to engage said stud and prevent operation of the lever, and means for operating said second slide to move the stud beyond the ledge and the shear blades into operative relation to the strip and then operating the pivoted shear blade to sever the strip.

53. In a machine for applying reinforcing strips to insoles, means for feeding an insole, strip-applying means movable toward and from an operating point, a treadle depression of which moves the strip-applying means toward the operating point, means adjacent to the operating point for cutting the strip, and means for preventing operation of the cutting means unless the treadle has been released.

54. In a machine for applying reinforcing strips to insoles, means for feeding an insole, strip-applying means movable toward and from an operating point, means adjacent to the operating point for cutting the strip, electro-magnetic means for operating the cutting means, a switch for controlling the electro-magnetic means, and means for preventing closing of the switch until

after the applying means has been moved away from the operating point.

55. In a machine for reinforcing welt insoles, means for feeding an insole, means for supplying a strip of fabric of indefinite length, means for applying the strip to the body of the insole and to the inner face of the rib, said means being movable from a remote inoperative position to an operative position adjacent to the feeding means, a pair of shear blades for cutting the strip, said blades being movable from an inoperative position to a position where the blades embrace the strip, a solenoid for operating the blades, and means for holding the solenoid circuit open until the strip-applying means has been moved away from operative position.

56. In a machine for reinforcing welt insoles, means for feeding the insole, strip-applying means movable from an inoperative position above the feeding means to an operating point adjacent to the feeding means, means adjacent to the feeding means for cutting the tape, and means for arresting movement of the applying means away from the operating point alternatively at different distances from the cutting point to provide long or short free ends on the strip.

57. In a machine for reinforcing ribbed insoles, an applying roll and strip guide movable toward and from an operating point, means for feeding an insole past said point to cause said applying roll to apply the strip to the insole, cutting means adjacent to the operating point for severing the strip, and means for arresting movement of the applying roll away from the cutting point at different distances therefrom to provide longer or shorter free ends on the strip.

58. In a machine for reinforcing ribbed insoles, an applying roll movable toward and from the operating point, means for feeding an insole past said point to cause said applying roll to apply the strip to the insole, cutting means adjacent to the operating point for severing the strip, a tip cam, and means engaging said cam to arrest movement of the applying roll away from the operating point alternatively at different distances therefrom to provide a longer or shorter free end on the strip.

59. In a machine for reinforcing insoles, means for feeding the insole, means for applying a strip of fabric to the insole, a pair of shears for cutting the strip, said shears being movable from an inoperative position to an operative position, and a guard in front of the shears to protect the operator from injury by the shears as they move to operative position.

60. In a machine for reinforcing ribbed insoles, means for feeding an insole, means for applying a portion of a strip of indefinite length to the body of the insole and to the inner face of the rib, a guard against which the work may be raised at the conclusion of the applying operation, means for cutting the strip adjacent to the guard, and a button adjacent to the guard for use in forming the end of the strip against the inner face of the rib.

61. In a machine for reinforcing ribbed insoles, means for feeding an insole past an operating point, an applying roll movable toward said operating point to apply a reinforcing strip, the free end of the strip at the beginning of the operation lying across the rib at the toe end of the insole, and means acting as the applying roll approaches the operating point to lay the free end of the

strip against the body of the insole and the rib at the toe.

62. In a machine for reinforcing ribbed insoles, means for feeding an insole past an operating point, a guard adjacent to the operating point, an applying roll movable toward and from the operating point and past the guard, means for arresting movement of the applying roll at a distance from the operating point to provide a long free end on the strip so that as the applying roll moves toward the operating point the free end of the strip will engage the guard and be turned upwardly, and means operated by the guard as the applying roll reaches applying position to lay the free end of the strip against the insole.

63. In a machine for reinforcing ribbed insoles, means for feeding an insole past an operating point, means for supplying a reinforcing strip of indefinite length, an applying roll movable toward said operating point to apply the reinforcing strip to the insole, the free end of the strip at the beginning of the operation lying across the rib at the toe end of the insole, and means acting automatically as the applying roll approaches the operating point to engage the free end of the strip and smooth it out against the body of the insole at the toe.

64. In a machine for reinforcing ribbed insoles, means for feeding an insole past an operating point, a guard adjacent to the operating point, an applying roll and strip guide movable toward and from the operating point and past the guard, means for providing a long free end on the strip so that as the applying roll moves toward the operating point the free end of the strip will be engaged by the guard and turned upwardly, and means operated by the guard as the applying roll reaches applying position to lay the free end of the strip against the insole.

65. In a machine for reinforcing ribbed insoles, means for applying a reinforcing strip to the body of an insole and to the inner face of the rib first along one side of the insole and then along the other so that the strips overlap at the toe end, and means for applying cement to the toe end of the first strip before the end of the second strip is laid over it.

66. In a machine for reinforcing ribbed insoles, means for applying a reinforcing strip to the body of an insole and to the inner face of the rib first along one side of the insole and then along the other so that the strips overlap at the toe end, and means operated by engagement with the rib of the insole for applying cement to the toe end of the first strip before the end of the second strip is laid over it.

67. In a machine for applying a strip of material stiffened with thermoplastic material to the rib and body of an insole to reinforce it, the combination of strip-laying means movable toward and from the insole, means for feeding the insole, strip-heating means, and means acting automatically as the applying means is moved toward the insole to cause relative movement of approach between the strip and the heating means to cause the strip to be heated prior to its application to the insole.

68. In a machine for applying strip material to shoe parts, the combination of strip-supplying means, means for applying the strip to the work, said applying means being movable toward and from its operating point, means for holding a portion of the strip in extended condition between the supplying means and the applying

means, means for moving the applying means toward the operating point, a heating device, and means acting as the applying means approaches the operating point to effect relative approaching movement between the heating device and the extended portion of the strip.

69. In a machine for applying strip material to shoe parts, the combination of strip-supplying means, a strip-applying roll movable toward and from its operating point, means for holding a portion of the strip in extended condition between the supplying means and the applying roll, manually operated means for moving the applying roll toward the operating point, a pivoted heating device, and means acting as the applying roll approaches the operating point to swing the heating device toward the extended portion of the strip.

70. In a machine for applying strip material to shoe parts, the combination of strip-supplying means, an applying roll movable toward and from its operating point, means for holding a portion of the strip in extended condition between the supplying means and the applying roll, a treadle for moving the applying roll toward the operating point, a heating device, and means acting as the applying roll approaches the operating point to effect mutual approaching movement between the heating device and the extended portion of the strip.

71. In a machine for applying a strip of material stiffened with thermoplastic material to the rib and body of an insole to reinforce it, the combination of strip-laying means movable toward and from the insole, means for feeding the insole, strip-heating means, a treadle for moving the strip-laying means toward the insole, and means acting automatically as the applying means is moved toward the insole to cause relative movement of approach between the strip and the heating means to cause the strip to be heated prior to its application to the insole.

72. In a machine for applying a strip of material stiffened with thermoplastic material to the rib and body of an insole to reinforce it, the combination of strip-laying means movable toward and from the insole, means for guiding the strip to the laying means, means for feeding the insole, strip-heating means pivoted to hang by gravity in a vertical plane, and means for moving the strip-laying means toward the insole and the guided strip toward the heating means, the strip-guiding means acting during the latter part of its movement to engage the strip-heating means and swing it toward the guided strip.

73. In a machine for applying a strip of material stiffened with thermoplastic material to the rib and body of an insole to reinforce it, the combination of means for feeding the insole, strip-laying means movable toward and from the insole, means for guiding the strip to the laying means, strip-heating means arranged for movement toward the strip-guiding means, means for moving the strip-laying means and the strip-guiding means toward the insole, means for simultaneously moving the heating means toward the strip-guiding means, means for arresting the heating means in proper relation to the strip-guiding means, and a yielding connection to permit further movement of the applying means into operative position after movement of the heating means is arrested.

CERTIFICATE OF CORRECTION.

Patent No. 2,242,248.

May 20, 1941.

STANLEY M. GRISWOLD, ET AL.

It is hereby certified that error appears in the printed specification of the above numbered patent requiring correction as follows: Page 2, second column, line 48, for "ond" read --and--; page 4, first column, line 44, for "at" read --in--; page 5, second column, line 42, for "behing" read --behind--; page 8, first column, line 42, for the word "guard" read --guide--; page 12, second column, line 24-25, claim 56, for "alternatively" read --alternately--; page 13, second column, line 53, claim 72, for the word "latter" read --later--; and that the said Letters Patent should be read with this correction therein that the same may conform to the record of the case in the Patent Office.

Signed and sealed this 24th day of June, A. D. 1941.
